UNITED STATES PATENT OFFICE.

ADOLF ANGST, OF SCHAFFHAUSEN, SWITZERLAND.

SAFETY RAZOR.

Application filed January 5, 1923. Serial No. 610,871.

To all whom it may concern:

Be it known that I, ADOLF ANGST, a citizen of the Republic of Switzerland, residing at Schaffhausen, Switzerland, have invented certain new and useful Improvements in Safety Razors, of which the following is a specification, reference being had therein to the accompanying drawing.

The subject of the present invention is a safety razor having a blade exchangeably mounted on a holder and a handle pivotally connected to said blade holder. According to the present invention the blade holder is provided with guide means comprising a guard rod arranged in front of the cutting edge of the blade and a guide plate arranged at the rear of the cutting edge, said guide means being at some distance from the cutting edge. Further a pivot connection is interposed between the blade holder and the handle which permits of an automatic adjustment of the blade holder relatively to and independently of the position of the handle, the axis of the pivots coinciding with the axis of the guard rod and a frictional resistance being provided influencing the relative turning movement between blade holder and handle.

Some parts of the blade holder may also serve as holding means for a blade when the latter is to be resharpened, whereby said parts ensure that the blade is held at the proper angle against the grinding surface.

In comparison with other known safety razors the safety razor according to the present invention shows the advantage that the blade will automatically adjust itself to the proper cutting position and independently of the position of the handle, and injuring of the skin when shaving is thereby practically excluded.

A constructional example of a safety razor according to the present invention is illustrated on the accompanying drawings, in which:

Fig. 1 is an end view, and

Fig. 2 shows in a side view part of the apparatus.

Fig. 3 is a view in the direction of the arrow III in Fig. 1 and shown on a smaller scale.

Figs. 4 and 5 show parts of the safety razor in the operative position for resharpening the blade, and

Fig. 6 shows the application of the safety razor.

The apparatus illustrated comprises a blade holder provided with a plate 1 on which the blade 2 is supported. The latter is held in position by means of a curved clamping piece 3, a guide plate 4 being arranged above the piece 3 and provided with two studs 5 projecting through perforations in the blade 2 and in the clamping piece 3. The guide plate 4 is further provided in its center part with a threaded pin 6 with which the nut 7 is in engagement for tightening the clamping piece 3. The holder plate 1 is bent in such a way that the cutting edge 8 of the flat blade 2 stands off the bent portion 9 of the holder plate 1. A slot 10 is arranged in the bent portion 9 and a guard rod 11 is provided above the slot. The guard rod 11 is rigidly fixed in arms 13 of a fork 14 and the holder plate 1 is provided with brackets 12 in which the rod 11 is rotatably mounted. The fork 14 is provided with a tapped socket into which the rod part 15 of the handle is screwed. The arms 13 of the fork 14 forming part of the handle are springy and press in a resilient manner against the brackets 12, whereby a certain frictional resistance is generated in the pivot connection between blade holder and handle. The rod part of the latter consists of two parts screwed together, the shortened parts permit of a compendious packing of the whole apparatus.

In Fig. 1 the apparatus is illustrated with its parts in the operative position for shaving. When the apparatus is moved along the skin the edge of the guide plate 4, the rod 11 and the edge of the part 9 act as guides to the blade holder. The cutting edge 8 of the blade 2 is adjusted by means of tightening the nut 7 more or less that it is in or approximately in the straight line *a*—*b* indicated in Fig. 1. This adjustment may be facilitated by providing the top face of the nut 7 with an index mark, such as indicated at 17 in Fig. 3 and adjusting said mark to points corresponding to the imagined figures on the dial of a watch, for instance the adjustment of the index mark 17 in Fig. 3 would correspond to XII on a watch. By means of this arrangement the adjustment of the blade edge which has proved most satisfactory is quickly performed again when the apparatus has been dismantled for cleaning purposes after use.

When the apparatus is pressed against the

skin during shaving the latter will assume the shape of a wave and the hairs are cut off from the wave so that it is not necessary to keep the skin stretched during the shave. 5 Owing to the pivot connection between blade holder and handle the blade holder adjusts itself automatically to the proper cutting positions, for instance into the positions I and II illustrated in Fig. 5, relatively to and independently of the position of the handle. The limits between which this adjustment takes place are indicated by the lines $a-b$ and a_1-b_1 , in Fig. 1.

In order to resharpen or strop a cutting edge of a used blade the latter is gripped between the clamping piece 3 and the guide plate 4, a plate, for instance an old blade 2' which has been made blunt, being inserted between the guide plate 4 and the blade to be resharpened and below the cutting edge of the latter which is not to be resharpened, as is shown in Figs. 4 and 5. The blade is then moved along the weavy line as indicated by the arrow IV in Fig. 5 over an even surface 16, for instance of leather or paper and covered with a grinding material, the nut 7 serving as a handle. The cutting angle of the edge of the blade 2, which corresponds to the respective angle of new blades, is maintained by the provision of a stud 18 inside the tapped part of the nut 7 which bears on the pin 6 when the nut is tightened to clamp the blade to be sharpened. In this manner no special ability is required for attaining a proper resharpening of used blades.

I claim:

1. A safety razor comprising in combination a blade holder and a blade exchangeably mounted on the former, guide means fixed on said blade holder and comprising a guard rod arranged in front of the cutting edge of the blade at some distance from said edge, and a handle pivotally connected to said blade holder, the axis of the pivot coinciding with the axis of said guard rod. 40

2. A safety razor comprising in combination a blade holder and a blade exchangeably mounted on the former, guide means fixed on said blade holder and comprising a guard rod arranged in front of the cutting edge of the blade at some distance from said edge, a handle pivotally connected to said blade holder, the axis of the pivot coinciding with the axis of said guard rod, and means adapted to generate a frictional resistance influencing the turning motions of the blade holder relatively to the handle in said pivotal connection. 50

3. A safety razor comprising in combination a blade holder and a blade exchangeably mounted on the former, guide means fixed on said blade holder and comprising a guard rod arranged in front of the cutting

edge of the blade and a guide plate in the rear of the cutting edge, the guide means being arranged at some distance from said edge, and a handle pivotally connected to said blade holder, the axis of the pivot coinciding with the axis of said guard rod. 70

4. A safety razor comprising in combination a blade holder and a blade exchangeably mounted on the former, guide means fixed on said blade holder and comprising a guard rod arranged in front of the cutting edge of the blade at some distance from said edge, brackets on said blade holder in which said guard rod is rotatably mounted, and a handle having a fork shaped end in which said guard rod is rigidly secured to provide for a pivotal connection between blade holder and handle. 75

5. A safety razor comprising in combination a blade holder consisting of a plate, a clamping piece and means to press the clamping piece against a blade inserted between the former and the plate, the latter having a bent portion and a slot provided therein, guide means fixed on said blade holder and comprising a guard rod arranged in front of the cutting edge at some distance from said edge and above said slot, brackets on said plate in which said guard rod is rotatably mounted, and a handle having a fork shaped end in which said guard rod is rigidly secured to provide for a pivotal connection between the blade holder and handle. 80

6. A safety razor comprising in combination a blade holder consisting of a plate, a clamping piece and means to press the clamping piece against a blade inserted between the former and the plate, the latter having a bent portion and a slot provided therein, guide means fixed on said blade holder and comprising a guard rod arranged in front of the cutting edge at some distance from said edge and above said slot, brackets on said plate in which said guard rod is rotatably mounted, and a handle having a fork shaped end in which said guard rod is rigidly secured to provide for a pivotal connection between blade holder and handle, the arms of the fork being springy to press against said brackets and to generate thereby a frictional resistance influencing the turning motions of the blade holder relatively to the handle in said pivotal connection. 100

7. A safety razor comprising in combination a blade holder consisting of a plate, a clamping piece and a nut cooperating with a stud on said plate for pressing the clamping piece against a blade inserted between the former and the plate, guide means fixed on said blade holder and comprising a guard rod arranged in front of the cutting edge and a guide plate in the back of the cutting edge, the guide means being arranged at some distance from said edge, said plate, 115

clamping piece, nut and guide plate forming also the means for holding a blade on being resharpened, brackets on said plate in which said guard rod is rotatably mounted, and a handle having a fork shaped end in which said guard rod is rigidly secured to provide for a pivotal connection between blade holder and handle, the arms of the fork being springy to press against said brackets and to generate thereby a frictional resistance influencing the turning motions of the blade holder relatively to the handle in said pivotal connection.

8. A safety razor comprising a blade hold-

er, a handle for the latter, and a guard rod 15 on the holder constituting a connecting member between the handle and holder.

9. A safety razor comprising a blade holder a guard rod journaled on the holder in front of the cutting edge of a blade mounted 20 on the holder, a handle, and means connecting the handle in fixed relation to the guard rod and in frictional relation with the blade holder, whereby the latter will automatically position the blade at an advantageous cut- 25 ting angle relative to the handle.

In testimony whereof I affix my signature.
ADOLF ANGST.
